UNITED STATES PATENT OFFICE.

LOUIS LEVITT AND ISIDOR RENDELMAN, OF NEW YORK, N. Y.

SAFETY-LOCK FOR MILK-BOTTLES.

1,139,780.

Specification of Letters Patent.

Patented May 18, 1915.

Application filed April 4, 1914. Serial No. 829,409.

To all whom it may concern:

Be it known that we, LOUIS LEVITT and ISIDOR RENDELMAN, citizens of the United States, and residents of New York city, borough of Brooklyn, in the county of Kings and State of New York, have invented certain new and useful Improvements in Safety-Locks for Milk-Bottles, of which the following is a specification.

10 This invention relates to safety locks for milk bottles.

In the usual course of delivery of milk bottles by the tradesman, the bottles are left outside the door where they may be taken 15 with little opportunity for detection.

The object of the present invention is, therefore, to provide a safety lock which may be left outside the door to be snapped over the bottle by the tradesman as he leaves 20 the same.

Another object is to provide a device of this character which is simple in construction and in operation and inexpensive to manufacture.

25 A further object is to provide means whereby a plurality of devices may be readily coupled together, and locked and unlocked with facility.

The various further objects and advantages will more fully appear from the detailed description and the features of novelty will be particularly pointed out in the 30 claims.

In the drawing illustrating this invention, 35 Figure 1 is a perspective view of the exterior of a house with a bottle outside of the door locked by our improved device. Fig. 2 is an elevation, partly in section, of the locking device as secured to the door and applied to the bottle. Fig. 3 is a section taken 40 along line 3—3 of Fig. 2. Fig. 4 is a plan view of the divided cap. Fig. 5 is a diagrammatic view on a reduced scale illustrating a number of caps strung on one chain. 45 Fig. 6 is an elevation illustrating a modified form of cap.

Referring particularly to Figs. 1 to 4 of the drawings, the improved safety lock consists of a cap formed preferably in two segmental sections or halves 10 and 11 hinged at the longitudinal edge thereof 12. At the interior of each section is riveted or otherwise attached a spring catch 13 which is adapted to snap under the bead 14 of the 50 bottle.

To lock the sections to each other, the latter are formed with registering ears 15 and 16 at their longitudinal edges. These ears are formed with registering perforations through which may pass a locking member 60 to be secured from the interior of the door. Any suitable locking member may be employed. Preferably, we use a chain 17 formed of a plurality of links which may be threaded through the perforations of the 65 registering ears, to effectually prevent relative movement therebetween, thus locking the sections together. At the upper end of the chain a ring 18 may be linked, thus preventing the removal of the chain from one 70 end, and at the other end of the chain is linked a special form of link 19 which hooks under the door and is of a size sufficiently small to pass freely through the registering 75 ears. This link is formed with a reduced flat portion 20 which fits under the door 21 and a pin 22 which may be used for threading the chain through the perforated ears.

In the use of our safety device, when it is 80 desired to leave the same ready for insertion upon the milk bottle by the tradesman, the cap is closed and the chain 17 threaded through the registering ears as hereinbefore described. The link 19 is then placed under 85 the door and the latter closed. This effectually prevents the removal of the cap and chain. When the tradesman delivers the bottle in the morning, he merely grasps the cap and snaps it over the neck of the 90 bottle, the springs 13 closing under the bead 14 and thus effectually preventing the removal of the bottle and cap until the door is opened and the link 19 freed, whereupon 95 the chain may be pulled out from the ears and the cap swung open. It will be noted that the bottom of the cap is made to contact the body of the bottle, so as to prevent the insertion of an instrument under the 100 springs to tamper with the same in an attempt to remove the cap.

In the diagrammatic view illustrated in Fig. 5, it will be noted that a plurality of caps A, B and C may be strung upon the same chain 17, so that a number of bottles 105 may be locked with the use of the same chain. When extra bottles are desired, it is merely necessary to string extra caps upon the chain.

In the modified form of cap illustrated in 110

Fig. 6, the cap sections 30 and 31 may be hinged together at point 32 adjacent the base of the cap and the locking ears 33 may be formed at the top of the cap. The usual chain or other locking member may pass through the registering ears as in the preferred construction illustrated and also snap springs may be disposed at the interior of the sections as previously explained.

10 It will be understood that the sections of the cap may be stamped out of sheet metal or they may be cast, in either event constituting a very inexpensive construction which may be supplied to the customer by 15 the tradesman supplying the milk or other article delivered in bottles.

The operation of the device is very simple and the same may be used by a person with very little or no mechanical skill.

20 Having thus described our invention, we claim as new and desire to secure by Letters Patent:

1. A safety lock for milk bottles comprising a cap formed of a plurality of sections, 25 flexible means disposed within the latter to snap over the neck of a bottle, registering ears at the free edges of the sections, and means passing through said registering ears and engaging under a door to lock the sections together and prevent theft of the bottle.

2. A safety lock for milk bottles comprising a cap formed of a plurality of sections, said sections having means for snapping 35 over the neck of a bottle, registering ears at the free edges of the sections, and flexible means passing through said registering ears

engaging under a door to lock the sections together and prevent theft of the bottle.

3. A safety lock for milk bottles comprising a cap formed of a plurality of sections which fit about the neck of a bottle, registering ears at the free edges of the sections, and flexible means passing through said registering ears comprising a link having a flattened portion passing under a door to lock the sections together and prevent theft of the bottle.

4. A safety lock for milk bottles comprising a cap formed of a plurality of sections said cap having means for snapping over the neck of a bottle, registering ears at the free edges of the sections, and a chain comprising a plurality of links passing through said registering ears engaging under a door to lock the sections together to prevent theft of the bottle.

5. A safety device for milk bottles comprising a plurality of caps, each cap formed of a plurality of sections adapted to snap over the neck of a bottle, registering ears at the free edges of the sections, and a flexible member passing through the registering ears in all of the caps to maintain the latter locked about the necks of the bottles.

Signed at New York city, in the county of New York, and State of New York, this 25th day of March, A. D. 1914.

LOUIS LEVITT.
ISIDOR RENDELMAN.
